AIR LOG

Edward P. Anderson, Rutherford, N. J., assignor
to Bendix Aviation Corporation, Teterboro,
N. J., a corporation of Delaware

Application November 27, 1943, Serial No. 512,013

13 Claims. (Cl. 73—183)

1

The present invention relates generally to air logs and particularly to a novel air mileage unit, such as may be used in systems for calculating air position or the like.

There are many methods of navigating and determining a mobile object's position, in combination with compass readings, from charts and tables based on computations involving functions such as, speed and distance. Calculations to determine air position or the like are usually made in "knots" (nautical miles per hour) for the reason that from a given position in azimuth of known latitude and longitude, a standard of set speed in nautical miles per hour will permit reasonably accurate calculations of air position provided substantially accurate measurements of airspeed and air mileage are taken. Such calculations are possible because of the knowledge that 90° along the earth is 5,400 nautical miles. Actually, the definition of the nautical mile is, that it is one minute of latitude so that $90^\circ = 90 \times 60 = 5,400$ minutes or nautical miles from the Equator to the poles. The earth is assumed for calculation purposes to be an exact sphere, although it is actually flattened at the poles.

Based on such knowledge, the air position of a craft for any instant may be determined from known functions of airspeed in nautical miles per hour from a position in azimuth and plotted on a chart, but the process of such calculations is laborious even for a trained navigator. Accordingly, numerous methods and apparatus for automatically determining air position of a craft in degrees latitude and longitude have been devised with some degree of success, but where close calculations are required and/or at high speeds, such systems are not dependable due to unsatisfactory means for obtaining functions of distance flown and true airspeed of the aircraft.

It is, therefore, one object of the present invention to provide improved novel means for measuring the air mileage flown by means of a member functioning at a speed proportional to the true airspeed of the aircraft.

Another object is to provide a novel means, whereby true airspeed measurement in minutes of latitude compensated for condition errors may be transmitted to any suitable computer means from which relative air position may be determined.

Another object is to provide in a novel true airspeed meter, a novel heat exchange system adapted to provide for control of errors due to density changes caused by compression.

2

Another object is to provide a novel system employing a pump, such as a centrifugal air compressor having a controlled pressure output, for measuring true airspeed in nautical miles per hour.

Another object is to provide a novel airspeed metering system including means responsive to the differential in pressure between pitot static and impact pressures, and the system pump pressure to thereby control power means adapted to actuate the pump, so as to maintain balance between such pressures under all prevailing conditions of flight.

Another object is to provide a novel air pump for the purpose described, which is constructed to dissipate compression heat, so as to maintain a more substantially constant temperature of air in the pump housing with respect to air outside the aircraft carrying the pump.

Yet another object of the invention is to provide a novel pump, which is simple to manufacture, easy to assemble, rugged, and constantly accurate in its metering of miles per hour in any system with which it is designed to be used.

The above and other objects and advantages of the present invention will appear more fully hereinafter from a consideration of the detailed description which follows, taken together with the accompanying drawings wherein several embodiments of the invention are illustrated.

It is to be expressly understood, however, that the drawings are for the purpose of illustration only and are not designed as a definition of the limits of the invention. Reference for this latter purpose should be had to the appended claims.

In the drawings, wherein like reference characters refer to like parts throughout the several views,

Figure 1 is a side elevation of one form of the novel air log or air mileage pump unit of the present invention.

Figure 2 is a schematic illustration to show the location of the pump unit and its connections with the control unit, relay amplifier circuit and atmospheric air.

Figure 3 is a diagrammatic illustration of the relay amplifier circuit.

Figure 4 is a bottom elevational view of the rotor chamber, showing an inlet cooling coil connected to the rotor shaft cap and an outlet nipple for connection to a control unit, as shown in Figure 2.

Figure 5 is a view partly in cross section illustrating one form of pump rotor construction.

Figure 6 is a broken section view of the rotor shown in Figure 5, pulled apart.

Figure 7 is a longitudinal side section view of the overall pump housing with an elevational view of the mechanism mounted therein.

Figure 8 is a top plan view of the overall pump housing.

Figure 9 is a longitudinal cross sectional view taken through both the pump overall housing and the pump rotor chamber.

Figure 10 is a cross-sectional view of one form of control unit mechanism removed from the casing.

Figure 11 is a front view partly in section of the control unit mechanism of Figure 10.

Figure 12 is a top plan view of the mechanism of Figure 11 taken along the line A—A thereof.

Figure 13 is a section view partly in elevation taken along the line B—B of Figure 12.

Figure 14 is a bottom plan view of the casing top for the mechanism shown in Figures 10 to 13.

Figure 15 is a front interior view of the casing with the top removed.

Figure 16 is a longitudinal cross section view of the casing with the top off.

Figure 17 is another form of control unit, wherein only one diaphragm is used.

Figure 18 is an exploded view of the several parts of the form shown in Figure 17.

The air log or air mileage system of the present invention is composed on an air pump, such as best shown in Figures 1, 7, and 9; control units, such as shown in Figures 10 to 18, and an amplifier and relay arrangement, such as is shown diagrammatically in Figure 3. Values of true airspeed can be obtained from this unit by any properly calibrated tachometer, and air miles can be determined by any properly calibrated counter. For example, the transmission between the pump and the tachometer used may be the usual flexible drive connection, which is rotated by the pump rotor, as hereinafter described, twenty-four (24) times for each nautical mile flown.

The several units of the present novel system will now be described in detail, reference being had first to Figure 9 of the drawings, wherein the novel air pump is shown. It includes an electric drive means, such as a series wound, D. C. motor 21. The motor 21 drives the centrifugal pump rotor 22 in an airtight housing composed of upper and lower sections 23 and 24, through motor drive shaft 25 and rotor driven shaft 26 coupled together by coupling 27, which is made of suitable heat insulating material, such as phenolic ring or the like to prevent heat from the motor being conducted to the pump. Each rotor housing section 23 and 24 has a plurality of heat radiator fins 20 projecting outwardly from their respective outer surfaces.

The pump shaft 26 enters the pump housing section 23 through a suitable sealing gland, such as a graphite sealing gland, which consists of a graphite ring 30 mounted in an airtight flexible disc 31. A nut 32 on the pump shaft 26 is threaded down, until its face is lightly bearing on the graphite ring 30, thus forming an air seal with a minimum of friction. The nut 32 may be locked by check nut 28.

The pump rotor 22 is a substantially perfect annular flat integrally formed metal disc drilled through along the diameter to provide a diametrical conduit 34. This diametrical conduit 34 connects with a T-coupling conduit 35 running down the pump shaft 26. At its lower end,

the pump shaft 26 passes through a second sealing gland 33, similar to the above described graphite ring 30 and flexible disc arrangement, and a metal cap 36 having cooling fins 37 is secured to the lower pump rotor housing section 24 by screws 38 or the like. A static air connection 40 is made to the inside of the cap 36 by means of metal tubing 41.

The static air from a suitable Pitot tube not shown, passes into tubing 41 at 63 and at 40 into cap 36, and then from the cap 36 through conduit 35 in the pump shaft 26 to the center of diametrical conduit 34 in the rotor 22 as shown by the arrows in Figure 9.

The pump shaft 26 is journaled in bearings in sections 23 and 24 of the airtight rotor housing. The pump bearings, may be of a type such as ball bearings 42 and 43, one being located above the pump rotor 22 and the other below it. The bearings 42 and 43 may be protected by a disc 44 of suitable material, which fits over the bearing race. This bearing may float in its retainer to permit end thrust, if desired in any well known manner.

The rotor housing, comprises two shallow cup sections 23 and 24 secured together around the rotor 22, each carrying their respective bearings 42 and 43, above described. The lower section 24 is drilled below and adjacent the periphery of rotor 22 to provide an outlet conduit 45 for pump pressure, shown in Figure 7, leading to a threaded nipple 46 for transmitting the pressure developed in the pump to a suitable control unit, such as described hereinafter in connection with Figures 11 through 16 and in the modification shown in Figures 17 and 18.

Another form of construction wherein the rotor may be formed of two parts 46¹ and 47 is shown in Figures 5 and 6. Parts 46¹ and 47 are provided with grooves or channels 48 extending completely across a surface diameter thereof in radial alignment on either side of pump shaft 26 centrally disposed through the rotor. When parts 46¹ and 47 are assembled by suitable means, such as by welding, an elongated tubular channel 50 is defined thereby, running directly through the rotor's inside diameter.

The motor 21 is mounted on support posts 52, which are part of the upper rotor housing 23, as shown in Figures 7 and 9. A mounting ring 53 of suitable heat insulating properties is located between the mounting lugs 54 on the motor 21 and the faced ends of posts 52, which serves to heat-insulate the pump rotor housing from the motor.

The main overall outer cover of the instrument is composed of three molded sections 55¹, 55 and 56 of "bakelite" or other desirable material. The top of cover section 55 is open to permit the motor 21 to extend upwardly therethrough and an auxiliary section or cap 55¹ is seated and sealed around the opening to close the top of the cover so that cooling air may be circulated through the jacket or cover and around the compressor housing and drive motor 21. Lugs 57 formed from the rotor housing sections 23 and 24 are used to mount and anchor the same in the bottom cover section 56, see Figures 4 and 7. The intermediate outer cover section 55 is then secured to the bottom outer section 56 by suitable fastening means such as, bolts 58, with a sealing gasket 59 between the sections to assure an airtight connection.

The lower section 56 of the main outer cover is provided with a relatively large inlet conduit 60 and the upper section 55 is provided with an

outlet conduit 61, as shown in Figure 9, whereby an additive cooling of the rotor housing is provided by circulation of cooling air around fins 20, and a relative temperature balance is maintained between the air in cooling coils 41 connected to a Pitot static outer coupling 63, shown in Figure 1, in the lower cover section 56 substantially in proportion to the air outside the pump.

The overall cover sections 55', 55 and 56 cup together, so as to form an outer casing around the pump rotor chamber, and the lower section 24 of the rotor housing may seat through lugs 57 on projections or shoulders 64 inside the lower section 56 of the overall casing, as shown in Figure 7. An opening in the lower section 56 may be provided, such as 65 for discharge of undesirable moisture formed from condensation, or this moisture may be drained back through the intake conduit 60.

A gear reduction box 66 may be located at the top of the motor 21, and contains speed reduction gearing adapted to drive flexible output shaft 67 to any suitable computer device, not shown. For example, the ratio of gear reduction may be about 62:1, and designed for revolving the output shaft 67 twenty-four (24) revolutions per nautical mile, as shown in Figures 7 and 9.

The motor 21 has a pair of power leads 69 and 70. The positive lead 69 is connected to the plug terminal 71 on the top of cover section 55, and the negative lead 70, shown in Figure 1 as a metallic sheath for lead 69 insulated therefrom in the usual manner, is connected to a metallic band on plug terminal 71. The lead 70 is anchored to a post or terminal 72 on cover section 55 with suitable leads to the binding terminals of the motor 21 as shown in Figure 7. A double condenser and choke, generally designated 73 connected to the terminals of the motor 21 and leads 69 and 70 so as to be interposed between the leads and the motor, may be attached inside the top cover section 55 to provide high frequency suppression for the motor 21, see Figure 7.

The entire pump unit is mounted on three mountings 74, such as double "Lord" type mountings or other well known anti-vibration mountings.

In lower section 56 of the pump unit cover are two threaded connections, such as static Pitot intake connection 63 connected to air cooled coil 41 and pump outlet connection 46 connected to a diaphragm of a control unit, as hereinafter described. Each connection 63 and 46 is sealed in the section 56 by sealing members 76 and 77, as shown in Figure 1.

The pump unit is connected to a control unit mounted in an airtight casing 80 see Figures 14, 15, and 16, one form being illustrated in detail in Figures 10, 11, 12 and 13 of the drawings. This unit is composed of two similar diaphragms 81 and 82 matched together and interchangeably mounted in pairs on a frame 83.

Pitot pressure is connected to the diaphragm 82 which directly operates a ratio lever 87, and pump pressure is connected to the diaphragm 81 which operates a link 85 connecting with the lever 87. The Pitot pressure may enter through any suitable dual coupling, such as 78. A light metal split stud or fork 79 is rigidly fixed to the pump diaphragm 81, and the link 85 is hinged in the stud 79.

At its other end, the link 85 is hinged within a fork bracket 86 to one end of ratio arm 87, thereby providing a differential linkage with approximately a 1:3 ratio. The other end of the

ratio arm 87 rests lightly on a rigidly fixed bridge 88 on the Pitot diaphragm 82, as in Figure 12. The pivot 89 of the ratio arm 87 is mounted in the fork bracket 86, which is attached by means of a fastener such as screw 90 to a metal block 91. The position of the fork bracket 86 on block 91 is adjustable for calibration purposes, movement of the fork bracket 86 along the direction of the ratio arm 87 effectively changing the ratio of the arm. The metal block 91 is rigidly attached to a shaft 92 which rotates in bearings 93 and 94; one bearing is in the frame 83, and the other bearing is in the brass plate 95 which screws or otherwise fastens to the bottom of the frame 83, as shown in Figure 13. A contact arm 96 is secured to the shaft 92, the contact 97 carried by the arm 96 wiping over a smooth insulating block 98 with another contact 99 embedded in it. The whole lever system is lightly spring loaded by means of a hairspring 100 on the shaft 92. This arrangement keeps the ratio arm 87 lightly bearing on the bridge 88 of the Pitot diaphragm 82.

A low pressure must be applied to the Pitot diaphragm before the wiping contact 97 reaches the contact 99 in the insulating block 98. This pressure represents the "cut-in" speed of approximately 50 miles per hour at which the pressure in the Pitot tube will actuate bellows 82 to operate the pump motor 21. If, after this speed has been reached the ratio of displacement of diaphragm 82 to diaphragm 81 is equal to that ratio of lever 87 to link 85, no motion will be transmitted through pivot 89 to the fork 86. Therefore, the shaft 92 will not rotate nor will the wiping contact 97 move. It is contact 97 which controls the current supply to the motor 21 which, in turn, controls the pump pressure supply to maintain a balance of displacements on the ratio arm 87. The pressure displacement relations for the diaphragms 81 and 82 are such that equal displacements correspond to approximately equal speed changes, except at low speeds. Since the order of the pump pressure is only $\frac{1}{6}$ that of the Pitot pressure, the ratio of the two displacements and hence that of the ratio arm 87 is about 3:1 (speed is proportional to $\sqrt{pressure}$). This is true since the ratio of movement of the shorter arm of lever 87 by the link 85 to the longer arm of said lever is about 1:3.

Because the speed displacement curves for the diaphragms 81 and 82 are not accurately linear, and because the diaphragms do not work over equal displacements, the pump would tend to run slow at high speeds, i. e., the diaphragm characteristics are such that the error which would arise owing to the lag in static pressure compressibility effect at such high speeds is over-corrected. This effect is corrected by means of a light leaf spring 101, best shown in Figure 12, which biases the extension of pump diaphragm 81 by resting on the diaphragm bridge 102. A series of threaded stops generally designated by numeral 103, which effectively vary the spring rate and force over the range of displacements of the diaphragm 81, are used for calibration purposes.

The insulating block 98 containing the fixed contact 99 is pivoted about a bolt 104, and its position is adjustable by means of an eccentric 105, Figure 10, which shifts the position of the opposite end of this block 98. The eccentric 105 is defined longitudinally around the split inner end of bolt 105 which snugly engages in a slotted or forked end of the block 98 to adjust the position of the latter and relation of the contacts 97 and 99 and avoid lost motion or play. A head 106a on

the bolt is countersunk in cover 106, and is held countersunk within the cover 106 by expansion spring 8 between the cover and washer 105b seated over radial pins 105c extending through the bolt or pin 105a. The adjustment affects both the "cut-in" speed and the calibration of the unit and is accessible from outside the casing through bolt head 106a which is sealed over with wax 106c after calibration, which seal must be broken for any readjustment.

A bi-metal rod 107, Figure 11, bearing on the pump diaphragm mounting bracket 108, compensates for temperature changes.

The entire mechanism is mounted in the "bakelite" housing 88. The main cover 106 is also of "bakelite," and a gasket between both cover and housing makes the interior airtight, as shown in Figures 14 to 16.

Static pressure is introduced into the housing 88 and around the diaphragms through the threaded bushing 109 in the rear of the housing. Two other bushings, 110 and 111, are provided for pump and Pitot pressure connections.

The wiping contact 97 is connected to the lug or terminal post 112 and wire 116 on the plate 95 through shaft 92 and spring 100, and the fixed contact 99 is connected to a one-pin plug 113 and wire 115. Lug 112 and plug 113 are arranged to coincide with openings 112a and 113a, respectively, in the cover 106.

Four mounting holes 114 are provided. It is not essential that the unit be secured on a shock-proof mounting, but the instrument must be mounted so that the diaphragms 81 and 82 are in a vertical plane to minimize the effects of position error.

In Figure 3 is illustrated an amplifier and relay circuit connected between the motor 21 for driving the pump rotor 22 and the control unit contacts 97 and 99, for example.

This circuit contains a gas filled tetrode having a control grid 122 and a plate 123. From a suitable rectifier power source positive lead 117 is connected to the plate 123 and by wire 115 to the stationary contact 99 of the control unit. Power lead 117 is further connected to a relay contact 120. A second relay contact 121 adapted to be connected to the contact 120 upon movement of the relay switch arm, is connected to the positive terminal 69 of the pump motor 21. The pump motor 21 is further connected by wire 70 to the negative (grounded) power lead 118 of said power source. Connected in parallel across the relay contacts 120 and 121 is a spark suppression circuit comprising a resistor R2 and a condenser C2.

To control the device as hereinbefore set forth, movable contact 97 is connected to terminal lug 112 and then by wire 116 through a resistor R3 to the negative power lead 118. Lead 116 is further connected through a resistor R4 to the control grid 122 of said tetrode. Said control grid is further connected to the negative power lead through a condenser C1. Connected across the power leads 117 and 118 is a variable resistor R, the tap-off of said resistor being connected through a relay coil adapted to control the closing and opening of contacts 120 and 121, to the cathode of said gas filled tetrode.

Condenser C1 and resistance R1 provide a time delay on pick up to prevent the relay contacts 120 and 121 from closing in response to fluctuations produced by vibrations in the control unit diaphragms 81 and 82. This reduces the number of impulses and interruptions in the circuit to the drive motor 21 and thus the fluctuations of

the pump rotor 22 while maintaining a balance between the pressures in the diaphragms 81 and 82.

When control contacts 97 and 99 close, the voltage across resistance R3 immediately becomes full line voltage instead of zero, but the voltage of grid 122 rises slowly owing to the time required to charge condenser C1 through resistance R1. When the voltage of grid 122 approaches line voltage, the current in plate 123 increases sufficiently to energize the relay to close contacts 120 and 121. When the contacts open again, the voltage in grid 122 drops slowly owing to discharge of condenser C1 through resistances R1 and R3.

After the voltage in grid 122 drops to approximately two volts, the current in plate 123 becomes insufficient to hold the relay energized. A variable resistor R is used to provide a small amount of fixed bias on the tube in order to reduce the plate current below the drop-off value of the relay when the contacts 97 and 99 open. A condenser C2 and resistor R2, may be provided as a relay arc quencher for the relay contacts 120 and 121, if desired.

The operation of the system should be apparent from the foregoing description, and briefly the principle involved in the operation of the air mileage unit is the balancing of Pitot pressure against pressure developed by a centrifugal pump rotor operating from static pressure and rotating in an airtight casing.

Pitot pressure, developed in the Pitot tube, is equal to $\frac{1}{2}MV^2$ (neglecting compressibility) where M is the air density and V is the true air-speed of the aircraft.

Pump pressure, developed by a centrifugal pump, such as described, is proportional to $\frac{1}{2}M_1V_1^2$, where M₁ is the air density at the center of the pump, and V₁ is the rate of rotation of the rotor periphery.

If the speed of pump rotor 22 is controlled to maintain a balance between Pitot pressure and pump pressure, and the density of the air at the center of the conduit 34 in pump rotor 22 equals the density of the air outside the aircraft, then the rate of rotation of the pump rotor will be proportional to the true airspeed of the aircraft. The two densities are kept equal with the pressure at a constant ratio, by connecting the center of the pump rotor 22 through conduit 35 in the pump shaft 26 to a source of static pressure 63, see Figure 1, and by maintaining the air inside the pump at outside air temperature by inducing a flow of air around the pump housing from outside the aircraft while simultaneously compensating for or dissipating compression heat assisted by the fins 20.

Thus when the speed of the rotor is such that its pressure output in diaphragm 81 exceeds the impact Pitot pressure in diaphragm 82, the relay contacts 120 and 121 are broken through the separation of control unit contacts 97 and 99, to thereby deenergize the motor 21, so that during flight the motor 21 is constantly energized and deenergized for intermittent periods to keep the number of rotor revolutions per hour closely corresponding to the airspeed of the craft carrying the same.

Another form of control unit is shown in Figures 17 and 18 mounted in an airtight casing 140. It comprises a pressure responsive member, such as diaphragm 141 interiorly connected to the pump outlet 45 at the nipple or connection 46 in the lower sections 24 and 56 of the air pump

rotor housing and cover through conduit 45, see Figures 7 and 9. The diaphragm 141 is mounted on a frame 142 secured therein, as by the coupling nipple 143.

Leading into housing 140 is another conduit 144 connected to a Pitot tube, not shown, whereby a differential in the pressure relation between pump pressure and Pitot impact pressure will actuate the diaphragm 141.

The frame 142 may be shaped as a rectangle having an off-set curved part over the front of diaphragm 141 at a point off-set with respect to the center bridge or loop 145 thereof, so as to provide arms 146 and 147 on each end of the curved part. Arms 146 and 147 are designed to mount the diaphragm actuated parts, hereinafter described.

Arm 147 supports a linkage system operated by diaphragm loop 145, which engages a crank lever or upright arm 148 fastened to one end of a slotted arm 148a of a spring bracket 148¹ secured to a rock shaft 149, which is journalled at its ends. On the inner end are bearing screws 149¹ adjustable in rods 150 and 151 depending from V-bracket 152 which in turn is secured by bolt 153 in elongated slot 154 to lug 155 of arm 147. The slot of the arm 148a receives the upper bearing screw 149¹ and a screw 148b serves to adjust the bracket and arm so that the lever or arm 148 will properly engage the bridge or loop 145 30 to respond to the movements of the diaphragm 141.

Extending upward from the other end of rock shaft 149 is rod 156, which in turn engages rod 157 extending at substantially right angles from hairspring shaft 158, to which an end of hairspring 159 is attached. The other end of the hairspring coil 159 is attached to the frame 142.

On shaft 158 spaced from rod 157 is movable contact arm 160 with a counterweight 161 on the extremity to one side of the hairspring shaft 158, and a contact point 162 on the other extremity connected to the wire 116.

Cooperating with the point 162 of arm 160 is an adjustable insulation or "bakelite" contact block 163 carried by the free end of curved arm 164 adapted to swing on pin 165 secured in the under side of flat top bar 166, which is secured to lugs 167 on frame 142, as by screws 168.

Adjustment of block 163 is accomplished by screw or bolt 169 swiveled in one end of the block 163, and threadable through bracket 170 secured to top bar 166, as by screws 171. Such adjustment will be necessary in high speed ships, so as to set for zero speed in proportion to the added weight of the compressed air within the centrifugal pump.

The diaphragm arrangement is set so that contraction thereof will close a circuit through contact arm 160 grounded to the frame 142 through which connection is made to the wire 116 and contact 172 embedded in the block 163 is connected in a relay circuit substantially as shown in Figure 3 through wire 115, which in turn supplies electrical power through relay contacts 120 and 121 to high speed motor 21 in driving connection with shaft 26 of the pump rotor 22 with the same time delay function as previously described in connection with the other form of control unit and the circuit shown in Figure 3.

When the speed of pump rotor 22 is such that its pressure exceeds the Pitot pressure, the control unit functions to actuate the relay through contacts 172 and 162 respectively in block 163 and arm 160, which are controlled by diaphragm

means 141 to break the circuit to motor 21 and to deenergize the same, so that during flight the motor 21 is constantly energized and deenergized for intermittent periods dampened or reduced by the time delay system above described to keep the revolutions of the rotor per hour closely corresponding to the speed of the craft.

The control unit of this form differs from the first form by providing only one diaphragm for maintenance of pump pressure to match the Pitot pressure, such Pitot pressure being maintained as representative of the air velocity about the ship. By constantly matching the representative Pitot pressure with pump pressure, the speed of the pump will be directly related to the airspeed in substantially the same manner as described in the operation of the first form of unit.

There is thus provided a novel arrangement and apparatus for determining air mileage and true airspeed with a novel air pump, the speed of rotation of which is suitably controlled, as by the novel units described in proportion to static pressures fed into the center of the rotor at inlet 63 and into part of the control unit at a temperature corresponding to the temperature of the air outside the aircraft, to thereby actuate a control adapted to maintain a balance between Pitot pressures, and the pump pressure; so that the speed of the pump rotor increases or decreases with respect to the time required to restore balance between the pump and Pitot pressures, following each change in the Pitot pressures, based on the fact that the rotor revolves twenty-four times for each nautical mile travelled in proportion to such changes in Pitot pressures brought about by the projection of an aircraft through the atmosphere.

Although only several embodiments of the invention have been illustrated and described, other changes and modifications, which will now appear to those skilled in the art, may be made without departing from the scope of the present invention. Reference is, therefore, to be had to the appended claims for a definition of the limits of the present invention.

What is claimed is:

1. An air log for determining the airspeed of an aircraft comprising in combination, a compressor having an air compressed chamber, an inlet and an outlet for said chamber, said inlet being connected to a source of static pressure leading to the center of said chamber; an outer jacket for said compressor, an inlet and an outlet for said jacket in communication with the atmospheric air outside the craft on which the device is mounted, a vacuum nozzle for said outlet, said atmospheric air in said outer jacket serving to cool said air compression chamber, an impact pressure source outside of the craft, and intermittent drive means for the compressor responsive to the differential between compressor outlet pressure and impact pressure derived from said impact pressure source outside said craft to thereby govern the speed of said compressor in proportion to the speed of the aircraft, said drive means having means to dampen fluctuations in the operation of the compressor.

2. Means for determining the airspeed of a craft comprising, an electrically driven compressor having an inlet and an outlet, said inlet being connected to a source of static air pressure, a casing for said compressor having an inlet connected to a source of static air pressure and an outlet provided with a vacuum nozzle in the slip stream of said craft, to maintain a sub-

stantially constant temperature balance between the static air pressure inlet and compressor pressure outlet, and the air surrounding said craft, means responsive to pressures discharged from said compressor, means connected to an impact air pressure source and responsive thereto, and means intermediate said responsive means to make and break an electrical circuit to said electrically driven compressor in proportion to the impact pressures developed in accordance with the speed of said craft to maintain a balance between said pressures.

3. In a device for determining airspeed, in combination with a suitable source of Pitot pressure having a static pressure line and an impact pressure line, a pressure controlled differential unit open to static pressure, a mechanical pressure chamber, an impeller in said chamber having a peripheral outlet, an impeller shaft, an inlet extending axially of said shaft to the axis of said impeller connected to said static pressure line and said outlet, an outlet coupling in said chamber adjacent the periphery of said impeller connected to said differential unit from said pump outlet, a casing for said compression chamber having an inlet and an outlet, said inlet being connected to a source of static air pressure, said outlet being provided with a vacuum nozzle to circulate the air about said compression chamber, and drive means for said impeller controlled by the differential between pump pressure and impact pressure with respect to static pressure in said differential unit.

4. An air pump for use in systems of the class described, comprising a rotor having a diametrically positioned exhaust conduit therethrough, a rotor chamber, a shaft having an axial intake defined therein extending to the conduit, a housing around said rotor chamber having an inlet and exhaust to atmospheric pressure, said exhaust being provided with a vacuum nozzle, an inlet conduit connected to said shaft intake from a suitable source of Pitot static pressure, and an outlet coupling adjacent the periphery of said rotor in said rotor chamber, said vacuum nozzle, housing and housing inlet being adapted to maintain the static pressure fed into the pump at a temperature substantially equal to the temperature of outside atmospheric air.

5. An air pump for use in systems of the class described, comprising a rotor having a diametrically positioned exhaust conduit therethrough, a rotor chamber provided with heat dissipating fins, a shaft having an axial intake defined therein, a housing around said rotor chamber having an inlet and exhaust to atmospheric pressure, a vacuum nozzle for said exhaust, an inlet coil coupled to said rotor shaft intake from a source of static pressure mounted in said housing adjacent said atmospheric inlet, whereby the air in the housing around the heat dissipating fins and the static air inside said coil are cooled substantially to the temperature of atmospheric air outside the housing to compensate for density changes caused by compression heat.

6. A centrifugal air log for measuring functions of airspeed, in combination with a drive means and a control unit for said drive means, comprising a housing, an inlet for said housing and an outlet provided with a vacuum nozzle to circulate air through said housing, an air compression chamber mounted in said housing having heat radiating fins extending therefrom in the path of said circulating air, a rotor in said chamber, a coil mounted in said housing connected to static

pressure outside said housing and disposed in the path of said circulating air, a pump shaft having an axial intake conduit therein connected to an end of said coil, to thereby deliver static air to the center of said rotor at a temperature substantially equal to atmospheric air, and an outlet coupling in said rotor chamber adjacent the periphery of said rotor connected to said control unit, to thereby control said pump drive means according to pressure values of the pump outlet and Pitot impact pressures as a function of airspeed.

7. A system for balancing a pump pressure output with a variable velocity pressure condition generated in accordance with the airspeed of an aircraft comprising an air pump, an electric motor for driving said pump, pressure switch means responsive to an unbalance between said pressures adapted to intermittently energize and de-energize said pump driving motor, and a relay circuit interconnected between said electric motor and said switch means, an amplifier tube having a plate and a control grid in said circuit with said switch means, a relay operated switch connected to the plate circuit of said tube and to said pump driving motor; operation of said pressure switch biasing said control grid to operate said tube, the resulting current in said plate circuit actuating said relay switch to operate said pump driving motor to maintain balance between pump pressures and velocity pressures in accordance with the airspeed of the aircraft.

8. A controller comprising, a rotatable shaft, a member fixed thereto, a lever pivoted to said member, one end of said lever being adapted to be moved by a linear force; a link, adapted to be moved by a second force, pivoted to the other end of said lever to balance said first force; a contact fixed to and movable with said shaft, and a stationary contact adapted to be engaged by said movable contact upon rotation of said shaft due to an unbalance of the two applied forces.

9. A controller comprising, a rotatable shaft, a member fixed thereto, a lever pivoted to said member, one end of said lever being adapted to be moved by a linear force; a link, adapted to be moved by a second force, pivoted to the other end of said lever to balance said first force; a contact fixed to and movable with said shaft, a stationary contact adapted to be engaged by said movable contact upon rotation of said shaft due to an unbalance of the two applied forces, and a temperature responsive element to correct the movement of said link during ambient temperature changes.

10. A controller comprising, a rotatable shaft, a member fixed thereto, a lever pivoted to said member, one end of said lever being adapted to be moved by a linear force; a link, adapted to be moved by a second force, pivoted to the other end of said lever to balance said first force; said first and second forces being of unequal magnitude, the lengths of the arms of said lever being in the same ratio as that of the two unequal forces, a contact fixed to and movable with said shaft, and a stationary contact adapted to be engaged by said movable contact upon rotation of said shaft due to an unbalance of the two applied forces.

11. A controller comprising, two opposed pressure responsive members adapted to be actuated respectively within two disproportionate pressure ranges, a rotatable shaft therebetween, a forked member fixed thereto; a lever pivoted to said forked member, one end of said lever being

adapted to be moved by the pressure member actuated within the higher pressure range, the ratio of the lengths of the two arms of said lever being of the same order as the ratio of the square roots of the two pressures applied; a link pivoted at one end to the other end of said lever adapted to be moved by the other of said pressure members to balance the pressure actuating said first pressure member, a contact fixed to said shaft and rotatable therewith, and a stationary contact adapted to be engaged by said movable contact upon rotation of said shaft due to an unbalance of the applied pressures.

12. A controller comprising, two opposed pressure responsive members adapted to be actuated respectively within two disproportionate pressure ranges, a rotatable shaft therebetween, a forked member fixed thereto; a lever pivoted to said forked member, one end of said lever being adapted to be moved by the pressure member actuated within the higher pressure range, the ratio of the lengths of the two arms of said lever being of the same order as the ratio of the square roots of the two pressures applied; a link pivoted at one end to the other end of said lever adapted to be moved by the other of said pressure members to balance the pressure actuating said first pressure member, variable resilient means associated with said second pressure responsive member for correcting the linear displacement of said member, a contact fixed to said shaft and rotatable therewith, a stationary contact adapted to be engaged by said movable contact upon rotation of said shaft due to an unbalance of the applied pressures, and a temperature responsive element to correct the linear movement of said second pressure responsive element for ambient temperature changes.

13. Means for determining the speed of a craft comprising a pump connected to a suitable source of static pressure, a motor for operating said pump, a pressure responsive member connected to a suitable source of impact pressure, a pres-

sure responsive member connected to said pump, a differential linkage interconnecting said pressure responsive members and balanced thereby, a switch actuated by the movement of said linkage upon an unbalance thereof by said members, a relay circuit controlled by the actuation of said switch to operate said motor for increasing the pressure delivered by said pump to said second member for rebalancing said linkage, and means included in said relay circuit to delay motor operation upon the actuation of said switch.

EDWARD P. ANDERSON.
